UNITED STATES PATENT OFFICE.

JOHN McMULLEN, OF BUFFALO, NEW YORK, ASSIGNOR TO W. H. MINER, INC., OF CHICAGO, ILLINOIS, A CORPORATION OF DELAWARE.

CAR CONSTRUCTION.

Application filed May 9, 1927. Serial No. 189,781.

This invention relates to improvements in car construction.

In the operation of railroads, experience has shown the advisability of so connecting the body bolster with the parts of the truck of the car that they cannot separate vertically in the event of collision or derailment, since this effectually prevents or minimizes turning over or telescoping of the cars. In the case of six-wheel trucks, where the center axle extends immediately beneath and closely adjacent to the center pin opening, it is practically impossible to apply the locking center pin from below.

One object of my invention is to provide in car construction a detachable king pin arrangement of an efficient type for locking together the body and truck bolsters of a car, and more specifically to provide a locking pin arrangement which may be detachably applied from the interior of the car above the truck and body bolster, and which includes a means whereby insertion of the pin in the center pin opening and a partial rotation thereof effects locking engagement between the parts, detachable means being provided which prevent rotation of the pin in a releasing direction.

Other objects of the invention will more clearly appear from the description and claims hereinafter following.

In the drawings, forming a part of this specification, Figure 1 is a vertical longitudinal sectional view of a portion of a car construction, taken partially through the center bearing of the car and showing my improvements in connection therewith. Figure 2 is a vertical transverse sectional view corresponding to the sectional line 2-2 of Figure 1; and Figure 3 is a horizontal sectional view through the truck member and center pin taken substantially upon the line 3-3 of Figure 1. And Figure 4 is a top plan view of the locking arrangement.

In said drawings, center sills of a built-up construction are shown, each of the same comprising a vertical plate 10 and upper and lower angular members 11-11 secured to the outer side thereof. Preferably another angle member 12 is secured to each plate along the lower edge thereof on the inner side as shown. In the car construction shown, the body bolster preferably includes an upper tension plate 13, and a lower compression plate 14, and connecting webs 140.

In carrying out my invention, I employ a body bolster center-bearing casting designated generally by the reference character A. The latter is provided with a bottom portion 15 adapted to rest upon the inner angle members 12-12 as shown, and has vertical side flanges 16-16, which are riveted to the inner faces of the center sill plates 10. Said center casting is provided with a plurality of transversely extending webs 17-17, and centrally of said casting there is provided an upstanding boss 18, having aligned center pin openings which register with a corresponding opening in the compression member 14 of the bolster, the top of the boss terminating a suitable distance below the tension plate 13, said tension plate being provided with an aperture 19 aligned with the apertures in the boss 18, and of somewhat greater diameter for the purpose of admitting the head of the center pin hereinafter more fully described.

On the under surface of the compression member 14, and centrally thereof, is arranged a center-bearing plate 20, having a recess 21 adapted for the reception of a central boss 22, forming a part of plate 23, which fits into a cup-shaped socket formed centrally in the truck bolster 150. The truck bolster or spider 150 preferably has formed integrally therewith a center-bearing section 24 which is provided with an upper central recess 25, and a lower central recess 26, said recesses being separated by means of a partition 27 in which is provided an elongated transversely disposed slot which affords communication between the chambers 25 and 26.

The locking center pin is indicated broadly by the reference character B. The center pin includes a cylindrical body portion 29 of a diameter permitting of the insertion of the pin through the openings in the body bolster, and into the recess 25, said pin being provided adjacent one end with a reduced portion 30, and at its extremity with a cross head 31 of narrow elongated conformation, and of such size as to be adapted to pass through the slot 28 in the partition 27 when the pin is being placed in operative condition, and enter the recess 26 in the bolster 150, and when rotated is disposed crosswise with respect to the slot 28 and cannot be removed past the partition 27. The opposite end of the pin is provided with a circular head 32 of greater diameter than the cylindrical body portion, said head being adapted to bear

against the top wall of the boss 18 as shown, there being any desired number of washers 33 interposed between the top of the boss 18 and the head 32 of the pin. The top surface 5 of the head 32 is provided with a diametrically arranged rib 34, adapted to cooperate with the means which prevent rotation of the pin when the same is in operative position.

- 10 Mounted upon the upper surface of the tension member 13 is a bracket 35 having a vertically disposed central section 36 extending upwardly through the floor 37 of the car, and preferably terminating flush with the upper surface thereof, said central section 15 being provided with a central bore 38 of somewhat greater diameter than the head 32 of the pin B. The upper portion of the central section 36 is provided with a square shoulder 39, adapted to accommodate a square 20 shaped locking plate 40 which may be secured in position by fastening members, such as the screws shown in the drawings. The under surface of the locking plate 40 is provided with downwardly projecting spaced ribs 25 42-42, between which the rib 34 on the pin B is received, which effectually prevents rotation of the pin B when the same is in operative condition, and thereby locks the truck 30 bolster 150 to the body bolster.
- 35 In operation, when it is desired to remove the locking pin B, the locking plate 40 is first disconnected and lifted vertically off of the square shoulder of the central section, after which the pin B is rotated about its axis to 40 position the cross head 31 so that the same may pass through the slot 28 in the truck bolster 150, the pin then being free to be vertically removed from the center pin openings, and thereby freeing the truck from its connection with the body bolster. When the truck is replaced after removal, the center plate 20 is first placed in position with respect to the center bearing 23, after which the desired number of washers may be slipped 45 upon the pin B after which said pin may be dropped through the central section into the pin openings of the boss 18, and said pin positioned so as to permit passage of the cross head 31 through the slot 28, after which the pin is rotated to dispose the same crosswise with respect to said slot, after which the locking plate 40 is applied and secured, thereby disposing the ribs 42-42 at opposite sides of the rib 34 on the pin, preventing rotation of 50 the pin, and locking the truck bolster to the body bolster, while permitting the necessary pivotal movement between the parts.

60 I have herein shown and described what I now consider the preferred manner of carrying out the invention, but the same is merely illustrative and all changes and modifications are contemplated that come within the scope of the claims appended hereto.

I claim:

- 65 1. In car construction, the combination

with a body bolster and a truck element, said truck element including centrally disposed locking means permitting the insertion of a locking member from the top of said element downwardly; of a locking member insertable 70 through the body bolster from the upper portion and having means cooperating, when moved in one direction, with said locking means to effect engagement therebetween and lock said body bolster and said truck element 75 together for pivotal movement; and detachable means for preventing movement of said member to release the locking engagement thereof with the parts.

2. In car construction, including a floor; 80 of a body bolster arranged beneath said floor; said body bolster being provided with king-pin openings; a truck member having king-pin openings adapted to register with the openings in said body bolster; a locking pin 85 insertable through the floor of said car and the openings of said body bolster and truck member; means associated with said body bolster and truck member and said pin whereby movement of said parts in one direction effects locking engagement between said bolster and truck member, while movement in a reverse direction releases said pin to permit detachment; and means accessible at a point 90 above the floor of said car for maintaining said pin in locking engagement or releasing the same for detachment.

3. In car construction, the combination 100 with a body bolster and a truck member, having means for the reception of a center pin; abutments on said pin, said body bolster and said truck member, adapted to be brought into engagement by relative rotation between the parts to lock said body bolster and truck member together for pivotal movement; and 105 detachable means, when in position, arranged to prevent relative rotation between the parts in a releasing direction, and when detached, freeing said pin for removal.

4. In car construction, the combination 110 with a body bolster and a truck member, having means for the reception of a center pin; abutments on said pin, said body bolster and said truck member adapted to be brought into engagement by relative rotation between the parts to lock said body bolster and truck member together for pivotal movement; and 115 detachable means, when in position, arranged to prevent relative rotation between the parts in a releasing direction, and when detached, 120 freeing said pin for removal.

5. In car construction, the combination 125 with a body bolster and a truck bolster having center pin openings, and abutments arranged to cooperate with a center pin, one of said abutments having an elongated slot therein; a center pin having a head adapted to engage the abutments of said body bolster, and the opposite end of said pin being provided with a reduced portion and a crosshead 130

adapted to enter said slot, rotation of said pin disposing said crosshead crosswise of said slot to prevent removal of said pin.

6. In car construction, the combination with a body bolster and a truck bolster having center pin openings, and abutments arranged to cooperate with a center pin, one of said abutments having an elongated slot therein; a center pin having a head adapted to engage the abutments of said body bolster, and the opposite end of said pin being provided with a reduced portion and a crosshead adapted to enter said slot, rotation of said pin disposing said crosshead crosswise of said slot to prevent removal of said pin; and detachable means accessible from the upper portion of said body bolster for locking said pin, said means being detachable to permit removal of said pin.
- 20 7. In a car construction, the combination with a body bolster provided with a center-pin opening; a truck element having a center-pin opening; a headed center-pin adapted to be disposed in the openings provided therefor; detachable means associated with the head of the pin and said body bolster to prevent or permit rotation thereof as desired; and means associated with the opposite end portion of said pin and with said truck element, whereby rotation of said pin locks and unlocks said truck element with respect to said body bolster.

8. In a car construction, including a floor provided with an opening, the combination with center sills and a body bolster including a center-bearing casting provided with a centrally disposed boss having bearing openings therein, of a central section secured to the upper portion of said bolster in spaced relation with reference to said boss, said section extending through the opening in said floor and terminating flush with the upper surface of said floor, said central section being provided with a central bore and having an off-set square shoulder adjacent its outer end; a truck member having center pin openings; a headed king pin disposed in the center opening, the head of said pin being arranged to bear against said boss, and the opposite end

of said pin having means by which rotation of said pin effects an interlocking connection with said truck member; and a square plate detachably arranged upon said shoulder, said plate being provided with a projection adapted to engage a projection upon the head of said pin when in operative position to prevent rotation of said pin.

9. In a device of the character described, the combination with a body bolster element and a truck element, each of said elements having king pin openings and central abutments, the abutments of one of said elements being spaced apart laterally to provide a recess of less width in one direction than the corresponding king pin opening; and a locking pin having abutments co-operating with the abutments of said elements, one of said abutments on said pin being of such a size as to pass freely through said recess in one position of the pin and being engageable with the abutments defining said recess by rotation of the pin to lock the bolster element and truck element together.

10. In a device of the character described, the combination with a body element and a truck element, each of said elements having king pin openings and central abutments, the abutments of one of said elements defining a recess of less width in one direction than the corresponding king pin opening; a locking pin having abutments adapted to co-operate with the abutments of said elements, one of said abutments on said pin being of a size to pass freely through said recess in one position of the pin and being engageable with the corresponding abutment by rotation of said pin to lock the bolster element and truck element together; and means located adjacent the entrance to the king pin openings, co-operating with the pin when in position to maintain its locking engagement, and when detached permitting removal of said pin from its locking position.

In witness that I claim the foregoing I have hereunto subscribed my name this 5th day of May 1927.

JOHN McMULLEN.
